UNITED STATES PATENT OFFICE

170,602

MEDALLION OR SIMILAR ARTICLE

Theresa C. O'Hare, Quincy, Mass.

Application February 11, 1953, Serial No. 23,560

Term of patent 7 years

(Cl. D45—19)

To all whom it may concern:

Be it known that I, Theresa C. O'Hare, a citizen of the United States, residing at Quincy, in the county of Norfolk, in the Commonwealth of Massachusetts, have invented a new, original, and ornamental Design for a Medallion or Similar Article, of which the following is a specification, reference being had to the accompanying drawing, forming a part thereof, in which:

I claim:

The ornamental design for a medallion or similar article, substantially as shown.

THERESA C. O'HARE.
